UNITED STATES PATENT OFFICE.

ROBERT SCHORR, OF SAN FRANCISCO, CALIFORNIA, ASSIGNOR TO MOORE-SCOTT IRON WORKS, OF SAN FRANCISCO, CALIFORNIA, A CORPORATION OF CALIFORNIA.

ADJUSTABLE LIQUID-ATOMIZER.

1,073,936.

Specification of Letters Patent. Patented Sept. 23, 1913.

Application filed April 5, 1912. Serial No. 688,792.

To all whom it may concern:

Be it known that I, ROBERT SCHORR, a citizen of the United States, residing at the city and county of San Francisco and State of California, have invented certain new and useful Improvements in Adjustable Liquid-Atomizers, of which the following is a specification.

The present invention relates to a novel atomizer for the spraying of liquid mechanically, *i. e.* under pressure and without the aid of steam or compressed air, as a fuel burner for use in connection with furnaces generally; the object being the production of a spraying or atomizing device of simple construction, inexpensive as to manufacture, efficient and economical in its operation, and one wherein an adjustment within given limits may be effected to vary the quantities of discharge without disturbing the arrangement of the associated parts relative to the furnace to which the atomizer is attached.

The improved atomizer comprises a novel construction of a holder and regulating means applied thereto, a longitudinally adjustable atomizing plug within the holder, straining means for removing foreign matter from within the liquid fuel as supplied to the atomizing plug, and a nozzle tip secured to the outer end of the holder and through which the atomized liquid is delivered directly into the furnace.

For the illustration of the invention there is shown in the drawings one form of a practical embodiment thereof as preferred in connection with the boilers of sea going vessels for the generation of steam, although it will be understood that the invention is not so restricted in its application, nor is the same limited to the precise construction and arrangement of the associated working instrumentalities hereinafter shown and described.

To comprehend the invention, reference should be had to the accompanying sheet of drawings wherein—

Figure 1 is a vertical sectional view of the improved atomizer disclosing the atomizing plug adjusted to full open position. Fig. 2 is a similar view illustrating the atomizing

plug in a partly closed position to reduce the quantity flow of liquid fuel therethrough, said view disclosing a modified form of adjusting means for the atomizing plug. Fig. 3 is a detail view of the atomizing plug detached from the atomizer.

In the drawings, the numeral 1 is used to designate any suitable form of a casting provided with an inlet 2 to which is secured one end of an oil supply pipe, also provided with an outlet 3 from which extends a tubular body 4 through which the liquid fuel passes, said body being preferably screwed into the outlet 3 so as to be readily attached to and detached therefrom. Within the casting 1 and extended within the inner end of the tubular body fitted therein is situated a strainer 5, the circumferential flange 6 of which is held against a circumferential shoulder 6' of the casting 1 by means of a perforated plate 7 fitted therein. The purpose of said strainer is obvious, the same being to break up the liquid fuel flowing toward the atomizing plug and to remove therefrom sediment and such foreign matter as would otherwise tend to clog or obstruct the outlet passages of the atomizer. The said strainer is fitted into the casting through an insertion opening 7' formed therein, which is closed by a plug 8.

To the outer or free end of the tubular body 4 is secured an atomizing or nozzle tip 9, the threaded extension 9' thereof screwing into the internally screw threaded end of the said body, a non-leaky joint being formed by means of a packing ring 10 interposed between the end of the said body and the exterior circumferential shoulder 11 of the nozzle tip 9. The nozzle tip 9 is provided with a centrally disposed outlet port 12, and the under face of said tip is recessed, as indicated at 13, in such a manner as to provide a cone shaped surface for directing and leading the atomized oil or liquid fuel toward the outlet port or orifice 12 of the nozzle tip, the outer wall of the said orifice being angularly inclined opposite to the wall of the recess 13. Within the extension 9' of the nozzle tip 9 is fitted for longitudinal movement a co-axial cylindrical atomizing

body or plug 14, the same being provided with one or more small vertical channels or bores 14^a, which, near the outer end of the plug, are turned sidewise or approximately 5 at right angle, as indicated at 14', in order that the fluid jets passing through the said plug may be directed outwardly to impinge tangentially upon the inside wall 15 of the enlarged chamber 15' of the nozzle tip 9. 10 The cylindrical extension 9' of the nozzle tip serves as a guide bearing for the atomizing plug 14, which plug is adjusted longitudinally relative to the said tip by means of the adjusting stem or spindle 16, which 15 screws into the said plug. This stem or spindle, which is of small diameter, extends through the tubular body 4, and strainer 5, the screw threaded end 17 thereof passing through a screw threaded bore 17' in the 20 perforated plate 7 and extending within the hollow plug 8. In order to adjust the position of the atomizing plug 14 relative to the nozzle tip 9, it is only required to remove the plug 8, when the stem may be turned to 25 move the atomizing plug in and out of the extension 9' to partly cover and uncover the tangential ports or channels 14' to decrease or increase the quantity flow of the atomized liquid under pressure into the mixing chamber 15' of the nozzle tip.

In Fig. 2 of the drawings, the perforated plate 7 is omitted, likewise the circumferential shoulder 6', the flange 6 of the strainer resting against the inner end of the 35 tubular body 4, and the end of the stem or spindle 16 extending into a socket 18 of the plug 8', being held thereto by means of a tap screw 18'. As thus connected it is only required to turn the screw plug 8' in 40 order to adjust the position of the atomizing plug to vary the quantity flow of the liquid fuel into the chamber 15' of the nozzle tip. While two ways of accomplishing this adjustment of the atomizing plug have been 45 illustrated and described, it is obvious that various other means may be resorted to. However, preference is given to the construction disclosed in Fig. 1 of the drawings, once made the same cannot be varied without 50 removing the plug 8, thus providing against accidental displacement of the adjusted parts.

When the atomizing plug is adjusted to full open position, the discharge ends of the 55 tangential ports 14' stand clear of the inner wall of the nozzle tip extension 9', Fig. 1 of the drawings, while when the flow of the liquid fuel is reduced by an inward adjustment of the atomizing plug 14 the discharge 60 ends of the said ports 14' are partly closed by the inner wall of the nozzle tip extension 9', Fig. 2 of the drawings. On the said atomizing plug being moved inward its full distance the discharge ends of the ports 14'

will be fully closed by the inner wall of 65 the extension 9' and the flow of the liquid will be entirely cut off.

In operation the tubular body is at all times filled with liquid under pressure which escapes into the chamber 15' in fine jet 70 streams through the channels or ports of the atomizing plug and by reason of the disposition of these ports and the pressure under which the liquid is held the same is delivered to the outlet orifice of the nozzle tip with a whirling action, escaping therefrom in the form of a fine atomized spray, the angle of inclination of the wall surrounding the said outlet orifice causing the spreading outwardly of the atomized liquid 80 stream.

By simply removing the nozzle tip 9 and the plug 8 all the parts are accessible for cleaning or other purposes, and inasmuch as no disk or other part is interposed between the atomizing plug and the nozzle tip, there is no interference with the free flow or discharge of the atomized liquid from the 85 nozzle tip.

I am aware that various devices have been 90 placed into use for atomizing liquid oil or fuel under pressure for the discharge of the atomized liquid with a whirling motion, such devices having been patented for a number of years, and no claim is made herein to the 95 same broadly; the present invention being restricted to the details of construction by means of which such action is produced.

In Fig. 2 of the drawings, the nozzle tip is illustrated as constructed in sections instead of an integral structure, that is, within the tip 9^a is fitted a perforated atomizing plate 19 which constitutes the central portion of the nozzle tip. However, preference is given to the construction of nozzle tip 100 illustrated in Fig. 1 of the drawings. The part 1 of the atomizer has been referred to as a casting, but such expression is employed to designate any form of a head member provided with an inlet and outlet for the 105 oil and to which the tubular body is united.

Having thus described the invention what is claimed as new and desired to be protected by Letters Patent is:—

In an atomizer for liquid fuel, the combination with a casting provided with an inlet and outlet opening for the liquid to be atomized, of a tubular body extended from the outlet opening of the casting, a perforated nozzle tip provided with an interior 115 chamber secured to the outer end of the tubular body, a co-axial cylindrical atomizing plug provided with fluid passages extended tangentially at their outer ends, said plug being longitudinally movable relative 120 to the nozzle tip, a strainer within the casting, a perforated plate for holding the strainer in position, a stem extended from 125

said plug through the tubular body, strainer and perforated plate for adjusting the position of the atomizing plug to vary the quantity of liquid passing therethrough to 5 the nozzle tip, an insertion opening within the casting, and means for closing said opening to protect the adjustable stem for the atomizing plug.

In testimony whereof I have signed my name to this specification in the presence of 10 two subscribing witnesses.

ROBERT SCHORR.
